DESIGN FOR A GAME BOARD

Frederick Adolph Kuehn, Portland, Oreg.

Application February 24, 1940, Serial No. 90,484

Term of patent 3½ years

To all whom it may concern:

Be it known that I, Frederick Adolph Kuehn, a citizen of the United States, residing at 7125 North Interstate Avenue, city of Portland, in the county of Multnomah and State of Oregon, have invented a new, original, and ornamental Design for Game Boards, of which the following is a specification, reference being had to the accompanying drawing, forming part thereof.

The figure is a plan view of a game board, showing my new design.

The article is of no appreciable or substantial thickness.

I claim:

The ornamental design for a game board, as shown and described.

FREDERICK ADOLPH KUEHN.
